(57) **CLAIM**

The ornamental design for a "saw blade tang" as shown and described.

DESCRIPTION

FIG. 1 is a front view of a saw blade tang, showing our new design;

FIG. 2 is a left view of the saw blade tang;

FIG. 3 is a right view of the saw blade tang;

FIG. 4 is a bottom view of the saw blade tang; and,

FIG. 5 is a top view of the saw blade tang.

The evenly spaced broken lines in FIGS. 1-5 are included to show features that form no part of the claimed design. The repeated one long and two short broken lines in FIG. 1 that define the bounds of the claimed design form no part thereof.
